UNITED STATES PATENT OFFICE.

BEECHER D. WHITCOMB, OF SHAWOMET, RHODE ISLAND.

ALARM FOR RAILROAD-CROSSINGS.

1,214,624.

Specification of Letters Patent.

Patented Feb. 6, 1917.

Application filed July 26, 1915. Serial No. 42,015.

To all whom it may concern:

Be it known that I, BEECHER D. WHITCOMB, a citizen of the United States, residing at Shawomet, in the county of Kent and 5 State of Rhode Island, have invented a new and useful Improvement in Alarms for Railroad-Crossings, of which the following is a specification.

This invention relates to certain new and 10 useful improvements in alarms for railroad crossings, and the primary object of the invention is to provide an alarm of improved and simplified construction, involving minimum of parts in its structure.

15 A further object of the invention is to provide novel means for controlling the return of the core to normal position following closing of the track circuit, and to also provide a novel form of circuit control for 20 causing the bell to stop ringing following actuation of the latter.

In the drawings—Figure 1 is a side elevation of the invention showing the parts in alarm sounding position, and Fig. 2 is a 25 similar view showing the parts in inoperative position.

In proceeding in accordance with the present invention a solenoid 1 is employed having a reciprocal core 2 therein, the core being 30 connected to a rod 3 upon which is loosely mounted a bridge bar 4, the latter being engaged on opposite sides by coil springs 5 and 6 which latter surround rod 3 and act to provide a balanced resilient mounting for 35 the bridge bar.

To the upper end of rod 3 a sprocket chain 7 is connected which latter is trained over a sprocket wheel 8 and a similar wheel 9 forming a part of a clockwork 10 having the 40 usual escapement 11. A weight 12 is connected to the pendant end of the chain.

The bridge bar 4 operates between a pair of lower contacts 13 and 13' and a similar pair of upper contacts 14 and 14'. A relay 45 including a magnet 15 is disposed to attract its armature 16 pivoted at 17, one end of which is adapted to contact with a spring element 18 and the other end with a contact 19. A wire 20 connects spring 18 with 50 a signal, here shown as a bell B, the latter being also connected by a wire 21, including a resistance 22, with a wire 23, which latter is connected to the solenoid winding. The negative pole 24 of the source of electrical 55 energy (not shown) is tapped onto wire 23. Wire 23, includes a resistance 25 and the

magnet winding 15 is tapped into wire 23 as depicted, the wire 23 being finally connected to contact 14.

A wire 26 connects each of the contacts 13' 60 and 14' and in turn is connected by a wire 27 to the magnet winding. A wire 28 leads from contact 13 to the positive feed wire 29, the latter connecting the trolley wire (not shown) to contact 19. Wire 27 leads 65 through the armature 16 as depicted. The wire 30 which is connected to the solenoid winding extends to a rail contactor.

The operation is as follows: The car (not 70 shown) is provided with a wiper or contactor connected with the positive trolley wire, to which latter the wire 29 is connected, so that when this contactor wipes the rail contact circuit will be made through rail contact wire 30, solenoid 1 and negative 75 terminal 24. The solenoid being thus energized, will attract the core 2 and draw same downwardly, causing the bridge 4 to contact with contacts 13 and 13' and closing the circuit through the latter, and at the same 80 time the weight 12 will be lifted by means of the chain and sprockets. The bridge 4 having closed the circuit through 13 and 13' the current will flow as indicated in solid 85 arrows from the positive feed wire across the bridge, thence through the relay attracting the armature or contact maker 16 and establishing a new circuit, will flow downwardly through the resistance 25, and thence to the negative feed wire 24. The 90 car having passed the contactor the clock movement, through the escapement, will permit the weight to slowly descend, thereby lifting the bridge as well as the core in slow and uniform manner. The circuit through 95 the bridge having been broken by lifting of the bridge the current will flow from the positive feed wire through the armature to the pivot of the latter where it will split, part passing through the tail of the armature, spring 18, through the alarm, through 100 the resistance 22 to the negative pole while the other part will pass through the relay downwardly to the resistance 25 and thence to the negative pole. The alarm being thus 105 sounded or otherwise if a signal other than a bell is used, will continue until the bridge has established the circuit shown in Fig. 2, when the current will flow from the positive main through the armature to the pivot 17 and owing to the resistance in the relay and the resistance 22 will pass from 17 up

110

wardly crossing the bridge, thence outwardly through the resistance 25 and finally to the negative wire, and as no current flows through the relay the armature, by reason 5 of the spring 18, will be disengaged from contact 19 and the circuit broken, thus effecting stoppage of the alarm.

Having thus described my invention, what I claim as new and desire to secure by Letters Patent is—

1. In a device of the character described, a normally opened signal circuit including a deenergized relay operable upon energization to close the circuit, said relay having 15 its armature pivoted between its ends, a spring adapted to be placed under tension by one end of the armature engaging therewith when the armature is attracted by its magnet whereby when the relay is short-circuited the spring will act as a restoring means for the armature, means for energizing the relay to close the circuit, and other means for short-circuiting the magnet of the relay to permit the spring performing 20 its function.

2. In a device of the character described, a relay, a main circuit including the relay armature and having spaced branch circuits, one branch circuit including a signal and 30 the other branch circuit including the relay magnet, a relay short-circuit, a relay initially-energizing circuit, and means for successively closing the last two circuits including a timing mechanism.

3. In a device of the character described, a relay, a main circuit including the relay armature and having spaced branch circuits, one branch circuit including a signal and 40 the other branch circuit including the relay magnet, a relay short-circuit having spaced contacts, a relay circuit for initially energizing the relay and having spaced contacts, and a single means movable between the contacts of the last two circuits to successively close the latter.

4. In a device of the type set forth, a normally opened signal circuit including a deenergized relay operable upon energization to close the circuit, a normally opened 50 branch circuit adapted to initially energize the relay, a short circuit wire normally opened and adapted when closed to short circuit the relay, and a single mechanism operable to successively electrically close the branch circuit and the short circuit wire.

5. In a device of the type set forth, a normally opened signal circuit including a deenergized relay operable upon energization to close the circuit, a normally opened

branch circuit adapted to initially energize the relay, a short circuit wire normally opened and adapted when closed to short circuit the relay, means operable to close successively and electrically the branch circuit and short circuit wire, and a timing mechanism operable to control the movement of said first means to close the short circuit wire.

6. In a device of the type set forth, a normally opened signal circuit including a deenergized relay operable upon energization to close the circuit, a normally opened branch circuit adapted to initially energize the relay, a short circuit wire normally opened and adapted when closed to short circuit the relay, means operable to close successively and electrically the branch circuit and short circuit wire, electro-magnetic means arranged to move said first means for closing the branch circuit, and means for actuating the first means to close the short circuit wire.

7. In a device of the type set forth, a normally opened signal circuit including a deenergized relay operable upon energization to close the circuit, a normally opened branch circuit adapted to initially energize the relay, a short circuit wire normally opened and adapted when closed to short circuit the relay, means operable to close successively and electrically the branch circuit and short circuit wire, electro-magnetic means arranged to move said first means for closing the branch circuit, and a time mechanism operable to move the first means to close the short circuit wire.

8. In a device of the type set forth, a normally opened signal circuit including a deenergized relay operable upon energization to close the circuit, a normally opened branch circuit adapted to initially energize the relay, a short circuit wire normally opened and adapted when closed to short circuit the relay, means operable to close successively and electrically the branch circuit and short circuit wire, electro-magnetic means arranged to move said first means for closing the branch circuit, and a motor operable upon release of the electro-magnetic means to move the first means for closing the short circuit wire.

In testimony whereof I have signed my name in the presence of two subscribing witnesses.
